UNITED STATES PATENT OFFICE.

GEORGE F. HUTCHINS, OF WORCESTER, MASSACHUSETTS, AND JAMES NIGHTINGALE, OF SUMMIT, NEW JERSEY.

LOOSE-REED MOTION FOR LOOMS.

SPECIFICATION forming part of Letters Patent No. 576,366, dated February 2, 1897.

Application filed May 21, 1896. Serial No. 592,398. (No model.)

To all whom it may concern:

Be it known that we, GEORGE F. HUTCHINS, residing at Worcester, in the county of Worcester and State of Massachusetts, and 5 JAMES NIGHTINGALE, residing at Summit, in the county of Union and State of New Jersey, citizens of the United States, have invented certain new and useful Improvements in Loose-Reed Motions for Looms, of which the 10 following is a specification.

Our invention relates to looms for weaving textile fabrics provided with spring-reeds, and more particularly to a supplemental attachment combined with the spring-reed; and the 15 object of our invention is to provide a supplemental mechanism combined with the spring-reed of a loom by means of which the reed will be caused to strike a sharp quick blow to beat up the filling just as the lay 20 reaches its forward position, thus making a fabric of closer and evener texture, particularly silk fabric.

Referring to the drawings, Figure 1 shows a portion of a loom side, one lay-sword, and a 25 sectional view of the breast-beam, lay, and spring-reed frame and our supplemental mechanism applied thereto. Fig. 2 shows the lay in a more forward position, with the spring-reed held back preparatory to being released 30 to beat up the filling. Fig. 3 shows the spring-reed released and in its forward position after it has beaten up the filling. Fig. 4 shows the lay going back and the spring-reed just being disengaged; and Figs. 5 and 6 show, on an 35 enlarged scale, perspective details of the two parts of our mechanism.

In the accompanying drawings, 1 is the loom side; 2, the breast-beam; 3, the lay, and 4 the lay-sword, pivoted at its lower end at 5 40 and operated by the crank-shaft 6, through the crank-connector 7, in the usual way. The reed 8 is pivotally supported at its upper side between uprights 9 at each end of the lay 3 by pins to swing in and out at its lower part, 45 which extends in a recess in the rear upper part of the lay in the usual way. A flat spring 11, secured at its lower end on the lay-sword 4, bears at its upper free end against the rear side of the reed 8. A screw 12 ex- 50 tends through the lay and may be turned in

or out to regulate the forward swing of the reed.

All of the above parts are of the ordinary construction and operation in the class of looms to which our supplemental mechanism 55 is intended to be applied.

We will now describe our mechanism to be combined with the spring-reed.

To the back of the swing-reed frame, near the end thereof, is secured a stand 13, having 60 an arm 13', which extends down below the lay, and is provided with a socket at its end, in which is adjustably secured, by a set-screw 14, a contact-piece 15, preferably of hardened steel.

A bracket 16 is secured to the under side of the breast-beam, and in this instance is slotted to receive the rear end of the knock-off lever or arm 17, which is pivoted to the bracket 16 by a bolt 18 and carries at its front 70 end in a socket therein a finger or contact piece 19, adjustably secured by a set-screw 20 and adapted to engage the contact-piece 15.

A coiled spring 21 extends in a recess in the bracket 16 and bears on the rear end 17' of 75 the knock-off lever 17 back of its pivotal support and acts to raise the front end of said lever 17. A projection 17" on said lever 17 engages with the projection 16" on the bracket 16 and limits the raising of said lever. The en- 80 gagement of the rear end 17' with the bracket 16 limits the downward motion of said lever.

A downwardly-extending projection 17'" on the lever 17 is adapted to be engaged by a screw 22, adjustable in an ear or lug 23 on 85 the lay-sword 4 and held in its adjusted position by two nuts 24 and 25. The screw 22 acts as a trip to engage the knock-off lever 17 on the forward movement of the lay and move it down to cause the finger 19 to be disengaged from the contact-piece 15 on the swing-reed 8, and allow the spring 11 to act to force the reed forward, as shown in Fig. 3.

From the above description, in connection with the drawings, the operation of our supplemental mechanism to operate the spring-reed will be readily understood by those skilled in the art.

As the lay beats up the finger 19 will engage with the contact-piece 15 and hold or re- 100

tard the reed 8 at its lower part. Just as the lay reaches the limit of its forward movement the screw 22, which is properly adjusted as desired, engages the lever 17 and moves it 5 down to trip or disengage the finger 19 from the piece 15 on the reed 8 and allow the spring 11 to act to force the lower part of the reed forward and cause it to beat up the filling with a sudden sharp blow.

10 It will be understood that the details of construction of our supplemental mechanism may be varied, if desired, and may be adapted to be combined with any spring-reed.

15 Having thus described our invention, what we claim as new, and desire to secure by Letters Patent, is—

1. In a loom, the combination with a spring-reed, of mechanism for stopping the forward movement of the reed on the forward motion 20 of the lay, and mechanism for releasing the reed, substantially as shown and described.

2. In a loom provided with a spring-reed, the combination with the reed having an arm thereon extending down below the reed, of a knock-off lever or arm pivotally supported in front of the lay, and provided with a finger adapted to engage the arm on the reed to stop the forward movement of the reed on the forward motion of the lay, and also provided with a projection adapted to be engaged by a screw or pin on the lay-sword on the forward movement of the lay, to move down said knock-off lever or arm, and release the reed, substantially as shown and described.

GEORGE F. HUTCHINS.

JAMES NIGHTINGALE.
